UNITED STATES PATENT OFFICE.

CHARLES H. METZ, OF SPOKANE, WASHINGTON.

BELT-PUNCH.

1,020,302.

Specification of Letters Patent. Patented Mar. 12, 1912.

Application filed September 14, 1911. Serial No. 649,225.

To all whom it may concern:

Be it known that I, CHARLES H. METZ, a citizen of the United States, and a resident of Spokane, in the county of Spokane and State of Washington, have invented an Improvement in Belt-Punches, of which the following is a specification.

My improved punch is provided with a peculiarly constructed point or cutting end which adapts it as a most efficient means for forming holes in belts and other articles.

The details of construction are herein-after described, and illustrated in the accompanying drawing, in which—

Figure 1 is a perspective view of the punch. Fig. 2 is a side view. Fig. 3 is a longitudinal section.

The body 1 of the punch is tubular and tapered and the cutting end is provided with a series of points 2 and intervening bevels 3 which form cutting edges. The points 2 are not beveled on the outer sides but are in line with the adjacent tapered portion of the body of the punch. The outer bevels 3 form flat surfaces which are extended upward or toward the head of the punch, being thus curved from one point 2

to another. It has been demonstrated in practical use that this form of cutter is highly effective for producing holes in leather and similar materials very smoothly and quickly.

In use, the punch is thrust and twisted or turned so that the beveled edges 3 finally cut entirely around the circle.

The punch makes a hole about twice the size of the core that is cut out. This is due to the taper on the outer side of the cutting edge. Thus less leather is cut out from a belt and the latter is not weakened at the point where the lace is applied and where the greatest strain occurs.

What I claim is:—

The improved tubular punch having a tapered body provided with a series of points whose outer sides are in line with the adjacent portion of the body, and flat outer bevels extending between the points and forming curved and sharp cutting edges, as shown and described.

CHARLES H. METZ.
